Primary Examiner — Ricky Pham(74) *Attorney, Agent, or Firm* — Moser Taboada(57) **CLAIM**

The ornamental design for a blender base, as shown and described.

DESCRIPTION

FIG. 1 is a front isometric view of a blender base embodying the new design;

FIG. 2 is a rear isometric view of the design shown in FIG. 1;

FIG. 3 is a top view of the design shown in FIG. 1;

FIG. 4 is a bottom view of the design shown in FIG. 1;

FIG. 5 is a left side view of the design shown in FIG. 1;

FIG. 6 is a right side view of the design shown in FIG. 1;

and,

FIG. 8 is a rear side view of the design shown in FIG. 1.
